Patented Dec. 27, 1921.

UNITED STATES PATENT OFFICE.

GEORGE H. QUAID, OF LOS ANGELES, CALIFORNIA.

SASH-WEIGHT.

1,401,441.

Specification of Letters Patent. Patented Dec. 27, 1921.

Application filed February 4, 1920. Serial No. 356,284.

To all whom it may concern:

Be it known that I, GEORGE H. QUAID, a citizen of the United States, residing at Los Angeles, in the county of Los Angeles and State of California, have invented a new and useful Sash-Weight, of which the following is a specification.

My invention relates to window construction, being more particularly sash weights and the manner of connecting the weights to the sashes.

One of the principal objects of my invention is to provide a sash weight for windows, of simple form and construction, the weight having a pulley which receives the cord, the ends of the cord being connected respectively to the upper and lower sash, the intermediate portions of the cord between the sashes and the pulley being supported in the window frame above the sash and also in providing means whereby the movement of the weight in the weight box may be stopped and the sashes operated in such a fashion as to counter balance each other.

Other objects and advantages will be made evident hereinafter.

Referring to the drawings which are for illustrative purposes only,

Figure 1 is a face view partly in section of a portion of a window showing a sash weight construction thereon embodying a form of my invention.

Fig. 2 is a vertical sectional view through a portion of the window frame, on line 2-2, Fig. 1.

Fig. 3 is a diagrammatic view showing the sashes, the weight and the cord connections.

Fig. 4 is an enlarged perspective view of a preferred form of sash weight used, and

Fig. 5 is an enlarged vertical sectional view through the locking device.

11 designates a window frame in which is mounted in the usual manner the upper sash 12 and the lower sash 13 of a window. 14 designates a sash weight which, in its preferred form, is made of concrete or other similar material, a rod 15 extending vertically through the weight and having secured to its upper end in any suitable manner a pulley 16. The under face of the weight is provided with transversely arranged grooves 18 which are arranged to be engaged by ribs 19 formed on the upper end of a block 20 which may be placed on

the rod 15 below the body 14 of the weight, the block 20 being held in place upon the rod by means of a suitable nut 21.

The under face of the block 20 is also 60 provided with grooves 22 extending across the same, and it is understood that a number of these blocks may be placed upon the rod and supported thereon by means of the nut, the number of blocks used being governed by the amount of weight necessary to 65 balance the weight of the sashes so that they can be easily operated.

25 designates a cord which extends through the pulley 16 and over sheaves 26 70 and 27 mounted in the window casing in any suitable manner above the sashes. One end of the cord 25 is secured to the upper end of the sash 12 and the other end of the cord 25 is secured to the upper end of the 75 lower sash 13.

The sash weight may be used in two different manners, that is, either one of the sashes 12 or 13 may be operated regardless of the other sash, in which case, the sash 80 weight will ride vertically in the weight box indicated at 28, which, it is understood, is placed in the window casing in the usual manner, or both sashes may be moved simultaneously by the operation of one sash 85 in the following manner:

Arranged in one side of the body 14 of the weight is a metal thimble 30. Upon the weight box 28 is mounted by means of suitable screws 31 a bolt housing 32 in which 90 may be placed, as shown in Fig. 5, a removable bolt 33, the inner end of which extends into the thimble 30 in the weight when the sashes are in closed position. When the bolt is in engagement with the 95 thimble as just described the weight is locked against movement in the weight box, and if for instance the lower sash is raised, the cord runs through the sheaves 26 and 27 and the pulley 16 so that as the lower sash rises the upper sash moves downwardly a corresponding distance, it being understood that any manipulation of one sash through the medium of the cord imparts a like movement to the other sash 100 in the opposite direction, the sashes balancing each other.

The bolt may be hung upon a chain 35, as shown clearly in Fig. 5, so that the bolt will not be misplaced when not in use.

110 It is understood that each side of the window embodies the same construction in

cluding the sash weight and cord connections hereinabove described.

I claim as my invention:—

A sash weight comprising a body of cementitious material, a rod extending vertically through said body having a threaded lower end, attaching means secured to the upper end of said rod, said body having grooves in its lower face, a block on said

rod below the body having ribs thereon corresponding to the grooves in said body, a nut on said rod below said block, and a bolt receiving member on one side of said body.

In testimony whereof, I have hereunto set my hand at Los Angeles, California, this 15 29th day of January, 1920.

GEORGE H. QUAID.
